UNITED STATES PATENT OFFICE.

LEVI E. LANE AND GEORGE HILLIARD, OF LYONS, NEW YORK.

WAGON-BRAKE.

SPECIFICATION forming part of Letters Patent No. 400,228, dated March 26, 1889.

Application filed November 17, 1888. Serial No. 291,169. (No model.)

To all whom it may concern:

Be it known that we, LEVI E. LANE and GEORGE HILLIARD, residents of Lyons, in the county of Wayne and State of New York, have invented certain new and useful Improvements in Automatic Wagon-Brakes; and we do hereby declare the following to be a full, clear, and exact description of the invention, such as will enable others skilled in the art to which it pertains to make and use the same.

This invention relates to brakes for vehicles; and it consists in certain improvements in the construction of the same, as hereininafter described and claimed.

In the accompanying drawings, Figure 1 is a plan view of the running-gear of a wagon provided with our improved brake. Fig. 2 is a side view of the same. Fig. 3 shows in front view the brake-bar and the arm supporting it. Fig. 4 is a view of the brake-shoe.

A designates the tongue of the wagon, the point of which is provided with a tube or sleeve, *a*, which is loosely placed thereon, the said tongue being reduced at the point and provided with a shoulder to limit the rearward movement of the sleeve, which is provided with a loop for connection with the neck-yoke.

To the sleeve *a* is secured one end of a rod, *b*, which extends rearward under the tongue, and is connected at its rear end with a yoke, *d*, which is formed of a bent rod, as shown. To retain the rod and the said yoke in place, they are loosely secured to the tongue and to the axle *B* by means of staples *c*.

C indicates the reach, which extends rearward from the front axle, *B*, and the bolster to the rear axle, *D*. In a slot in the said reach near its forward end is pivoted a short lever, *f*, the lower end of which is formed to hook on the rear part of the yoke *d*, which is formed on a part of a circle, as shown, so that it will slide in the hook on lever *f* when the front axle, *B*, is turned in either direction. Another short lever, *g*, is pivoted to the reach some distance rearward from the lever *f*, and a connecting-rod, *h*, connects the upper end of lever *f* with the upper end of lever *g*, the rear end of said rod being slotted and perforated for the purpose of adjusting the rod in

length between the two levers, as may be found necessary. The upper end of the lever *g* is slotted to allow a movement of the rod *h*, the rear end of which rises when the brake is closed.

To the lower end of the lever *g* is secured the rear end of a connecting-rod, *k*, the forward end of said rod being bifurcated and connected with the brake-bar *m*, which carries the brake-shoes *n*, which are in position to be closed against the hind wheels, *E*, of the wagon, as shown. Two arms, *p*, are fastened to the reach *C* and extend at right angles therefrom, as shown, the extremities of said arms being united and bent downward and forward, so that they form supports for the brake-rod *m* at points near the shoes *n*. The brake-rod *m* is further supported by the yoke *r*, which is fastened thereto and which is also attached to the reach *C*, and has its movement forward or rearward as the brake is operated. The shoes *n* are pivotally connected with the brake-bar, and are provided with springs *v*, which serve to retain them in position to close against the wheels. In backing the vehicle the shoes are automatically turned upward on their pivots by the rotation of the wheels, the springs allowing the shoes to turn on the brake-bar, and thus only a minimum degree of frictional resistance is offered by the brake-blocks to the wheels.

As will be seen, the brake-rod *m* is supported in position below the plane of the axle of the rear wheels, so that when the brake is closed against said wheels in backing the team the rearward revolution of said wheels is not prevented by the binding of the shoes *n* against them, but the revolution of said wheels in the opposite direction, as in the forward movement of the vehicle, will be immediately stopped by the closing of the shoes against them.

The bolt *s*, by which the whiffletree is secured to the tongue, is passed through a slot, *u*, in the hammer-strap *w* and through a slot in the tongue, and the lower end of the bolt is connected with the rod *b*, so that when the vehicle is drawn forward the rod *b* is drawn, and through the rearward connections of said rod the brake is moved from the wheels *E*.

The closing of the brake against the wheels

is effected by simply checking or backing the team, whereby the sleeve *a* is pushed back, thus moving rearward the rod *b* and operating the pivotal levers and connecting-rods, 5 through which the brake is closed against the wheels.

We claim—

1. In a vehicle, the combination of the sleeve adapted to slide longitudinally on the tongue, the yoke *d*, also adapted to slide, connected to the sleeve and having its curved rear portion, the lever *f*, pivoted to the reach and having its lower end engaging the curved portion of the yoke, the lever *g*, also pivoted 10 to the reach, the rod *h*, connecting the upper ends of levers *f* *g*, the brake-bar suspended from and having the supporting-yokes sliding on the reach, and the bar *k*, connecting

the lower end of the lever *g* to the brake-bar, substantially as described.

2. In an automatic vehicle-brake apparatus, 20 the brake-bar, the brake-shoes pivoted thereon and adapted to turn axially, and the inverted-V-shaped springs *v*, each having one end secured to the pivotal part of the brake-bar and the other end attached to one of the brake-shoes, for the purpose set forth, substantially as described.

In testimony whereof we have signed this specification in the presence of two subscribers.

LEVI E. LANE.
GEORGE HILLIARD.
